CLAIM

The ornamental design for a golf club, as shown and described.

DESCRIPTION

FIG. 1 is a bottom, right, and front isometric view of an ornamental design for a golf club;

FIG. 2 is a front elevational view of the golf club of FIG. 1;
FIG. 3 is a rear elevational view of the golf club of FIG. 1;
FIG. 4 is a right side elevational view of the golf club of FIG. 1;

FIG. 5 is a left side elevational view of the golf club of FIG. 1; and,
FIG. 6 is a bottom plan view of the golf club of FIG. 1.
The dash-dash-dash broken lines illustrate portions of the golf club that form no part of the claimed design.
